UNITED STATES PATENT OFFICE.

WILLIAM E. DAMANT, OF WEST HOBOKEN, NEW JERSEY, ASSIGNOR TO HIMSELF AND WILLIAM HESSIN, OF TORONTO, CANADA.

IMPROVEMENT IN APPARATUS FOR PREPARING THE PASTE FOR LOZENGE-CUTTING MACHINES.

Specification forming part of Letters Patent No. 113,635, dated April 11, 1871; reissue No. 5,100, dated October 15, 1872; reissue No. 5,171, dated December 3, 1872.

DIVISION B.

To all whom it may concern:

Be it known that WILLIAM EDWARD DAMANT, of West Hoboken, in the county of Hudson and State of New Jersey, has invented a new and Improved Machine for Rolling Dough and Paste, of which the following is a specification:

The drawing represents a vertical longitudinal section of the improved machine for rolling dough, paste, &c.

This invention relates to a new machine for flattening out the dough and paste used in the manufacture of confectionery, biscuits, &c., while feeding the same to the apparatus on which such dough or paste is subsequently cut or shaped. The invention consists in the combination, with each other, of two or more pairs of endless aprons, between which the dough is gradually compressed or flattened out to the requisite thinness. The invention also consists in the combination of starch-boxes having perforated bottoms with the above-mentioned aprons, the boxes being secured above the aprons to deposit thin layers of starch or equivalent substances thereon for preventing the adhesion of the dough thereto.

A, A², A³, A⁴, A⁵, and A⁶ in the drawing are three pairs of endless aprons, arranged parallel to each other, but at different altitudes, on rollers a a, &c., whose bearings are in a stationary frame, B. One end of the apron A is a short distance above one end of the apron A², as shown; so is also one end of A³ above A⁴, and one end of A⁵ above one end of A⁶, the overlying ends of each pair of aprons being the inner ends, or in the inner part of the frame B, as shown. The space between the aprons A and A² is larger than that between A³ and A⁴, and this again larger than the space between A⁵ and A⁶. An inclined stationary board or platform, b, extends from the inner end of the apron A² to the apron A⁴; likewise one from the inner end of A⁴ to A⁶, and also one from the end of A⁶ to a belt or feeding apparatus, C, by which the compressed or flattened dough is finally delivered

to the cutting or shaping mechanism. These inclines b b may, however, be dispensed with if the aprons A² and A⁴, and A⁴ and A⁶, and A⁶ and C are placed so close together that one may discharge directly to the other. Above every one of the aprons A to A⁶ is placed a box, D, which has a perforated or bolting cloth bottom, d, the bottom being close above the upper surface of each respective apron.

Starch or equivalent substance is put into the box D, and thence gradually deposited upon the aprons to prevent the adhesion to the latter of the paste or dough. The paste is fed to the apron A², and by the same conveyed in the direction of the arrow under the apron A. Between A and A² the paste is compressed into a thinner sheet than that in which it was fed to A². From the apron A² the paste thus compressed is deposited upon A⁴, and still more compressed under A³; then deposited upon A⁶; more flattened yet under A⁵, and finally discharged upon the receiver C. The paste is thus automatically and gradually flattened out into condition for being cut or shaped.

For many cases two pairs of aprons may answer instead of three.

Claims.

1. The combination with each other of two or more pairs of aprons, arranged one set above another, and with gradually diminishing spaces between every succeeding pair of rolls, substantially as and for the purpose herein shown and described.
2. The combination, with subject-matter of first claim, of the starch-boxes W W, arranged substantially as herein shown and described.

WILLIAM EDWARD DAMANT.

WILLIAM HESSIN.
